UNITED STATES PATENT OFFICE.

OSCAR A. SMITH, OF CLEVELAND, OHIO.

PRIMING AND TESTING CUP.

1,304,111.

Specification of Letters Patent. Patented May 20, 1919.

Application filed February 5, 1918. Serial No. 215,510.

To all whom it may concern:

Be it known that I, OSCAR A. SMITH, a citizen of the United States, residing at Cleveland, in the county of Cuyahoga and State of Ohio, have invented certain new and useful Improvements in Priming and Testing Cups, of which the following is a specification.

This invention relates to priming and testing cups for gas engines, the object of the invention being to provide an improved cup having all the advantages of the cup described in my Patent No. 1,153,457, dated September 14, 1915 and in my contemporaneously pending application filed November 8, 1917, Serial No. 200,869, it being an improvement in part particularly upon said application in that the present improvement has the important advantage that it can be used either with upright motors or motors that are located at an angle, such as 8-cylinder and 12-cylinder motors, and can also be placed in the side of such motors instead of the top, if so desired, and also the further advantage that the valve stem extends through the device from end to end axially thereof.

A further important advantage resides in the fact that the device can be much less expensively made in view of the elimination of certain features in my prior patent and applications.

In my prior patent the cup therein shown necessarily had to be inserted into the motor casing at the top thereof and the cups of my application Serial No. 200,869 were intended for use primarily with motors located at an angle to the perpendicular. While the present improvement is also intended for use with motors located at an angle to the perpendicular, nevertheless it can also be used to advantage with upright motors.

In the drawings accompanying and forming a part of this specification, Figure 1 is a vertical sectional view of this improved priming and testing cup, the dotted lines illustrating the valve partly open; Fig. 2 is a top view thereof; and Fig. 3 is a side view thereof.

Similar characters of reference indicate corresponding parts in the several figures of the drawing.

In the present improvement, like that shown in my prior patent and application,

the valve is maintained closed by pressure thereon. Moreover, by reason of the construction, the carbon and soot cannot close or clog up the opening or passage-way since any that forms on the valve is fractured 60 when the valve is opened, as the valve passage, by reason of the manner in which the valve opens and closes, is entirely cut off from the combustion chamber of the engine, and moreover by means of the present 65 construction the valve is proof against leakage, so that it is always possible to easily manipulate the valve without liability of the carbon injuring the valve seat or valve, and thus the valve can always be maintained 70 tightly seated and so prevent any possible loss of power resulting from an improper seating of the valve.

This improved priming and testing cup comprises a tubular portion 2 and a cup portion 3 having preferably at their juncture points a hexagonal nut portion 4 for the reception of a wrench. The tubular portion is provided with exterior threads 5 at its lower end, so that the device may be turned into the 75 motor and is also provided with a tapered 80 valve seat 6 communicating with the axial or tubular passage-way 7 of the tubular portion 2. The cup portion 3 is provided at its upper end with an opening 8 of less diameter than the tubular passage-way, but in axial alignment therewith, and this opening is provided with interior threads 9, and to one side of this opening and inclined to the axis of the tubular passage-way the device 85 is provided with a cup or chamber 10 opening directly into the axial passage-way of the tubular portion and around the stem of the valve about to be described. This chamber is thus so located that even though the 90 device may be placed at the side of,—that is, horizontally into the engine,—instead of at the top or at an angle thereto, the fluid will 95 not run out.

It will be observed that the top 11 of the 100 device is in a horizontal plane while the top 12 of the chamber is located inclined or at an angle to said top 11.

Projecting through the threaded opening at the top and through the tubular passage-way is a valve stem carrying at its lower end a tapered valve adapted to engage the valve seat hereinbefore described. This valve stem is provided with threads at its upper end adapted to engage the interior threads 105 110

9 of the opening 8. The valve stem is bent at an angle as at 13 to provide a suitable handle.

From the foregoing, it will be observed that the threads for locking the valve against its seat are located at the upper end of the device instead of at the lower end thereof as in my prior patent and applications, thus I am enabled to do away with certain machine work heretofore required in forming grooves or slots communicating with the axial passage-way, while I am also enabled to provide a much larger opening for the passage of fluid through the valve since the valve stem does not have to be made enlarged at its lower end as heretofore for the purpose of carrying the threads as the threads at the upper end in the present structure are out of the way.

20 It will thus be observed that while retaining all the advantages of my prior patent and applications, I have provided an improved cup which can be used at the top or at the side of either an upright or a V-shaped motor, and also have materially simplified and lessened the machine work of such cups.

From the foregoing it will be seen that the present improved cup comprises a body portion having an axial passage-way therethrough from end to end and which body portion is provided with a passage or angularly located chamber which communicates with the axial passage-way of the body below the top thereof, and which chamber is so located that whether it is in an upright, inclined or horizontal position, the fluid will not run out thereof except through such passage-way.

Moreover it will be observed that the passage-way from its point of communication with the chamber is larger than that portion of the passage-way which is interiorly threaded and this provides not only means for the quick egress of the fluid but for the proper assemblage of the parts since the valve stem, before the handle is bent and flattened may be readily inserted from the bottom of the cup into position, after which, of course, the handle is bent, or flattened if desired, or both and this prevents the detachment of the handle from its proper position since the handle may be bent at just the right place to permit the valve to be opened to its full extent only.

55 It will be understood that the various details may be more or less departed from without departing from the spirit or scope of the present improvement.

I claim as my invention:

60 1. A priming and testing cup comprising a two part device, one comprising a body having a passage therethrough and provided with a valve seat at its lower end and a chamber projecting to one side of and in communication with said passage below the

top of said body and so located that the longitudinal axis of said chamber is adapted to be placed in a vertical plane when the body is located in an inclined position, and the other a valve for closing said seat and having a stem extending through said passage, said body and stem having adjacent to the upper end of said body cooperating threads for holding the valve in its closed or open position, the diameter of the passage from the valve seat to its point of communication with the chamber being greater than the diameter of the passage adjacent to said cooperating threads, the opening of the valve being effected by lowering said valve from its seat in the direction of the flow of the fluid through said passage, said body also having exteriorly of its valve seat threads and also having a wrench receiving portion.

2. A priming and testing cup comprising a tubular portion having exterior threads and a valve seat at its lower end and having at its upper end an angularly located chamber and also having at one side of the upper part of said chamber an interiorly threaded opening, the top of said cup being in a plane substantially parallel to the bottom thereof, and the top of said chamber being inclined to said top, a valve stem extending through said threaded opening and tubular portions and having a valve at its lower end, a handle at its upper end and threads adapted to engage said threaded opening.

3. A priming and testing cup comprising a body having a passage therethrough from end to end and terminating at its lower end in a valve seat and having at its upper end interior threads, a valve for closing said seat and provided with a stem extending through said passage and having threads for engaging the interior threads of said opening, said body having an offset chamber between its ends and in communication with said passage below said interior threads and so located that the longitudinal axis of said chamber is adapted to be placed in a vertical plane when the body is located in an inclined position, the opening of the valve being effected by lowering said valve from its seat in the direction of the flow of the fluid through said passage.

4. A priming and testing cup comprising a body having a passage from end to end and at its lower end a valve seat and having adjacent to its upper end a chamber extending at an angle thereto and in communication with said passage below the top of said body and so located that the longitudinal axis of said chamber is adapted to be placed in a vertical plane when the body is located in an inclined position, said body also having at one side of said chamber interior threads and a valve adapted to engage said seat and having a stem provided with cooperating threads.

5. A priming and testing cup comprising a body having an axial passage from end to end thereof and also having at its lower end exterior threads and a tapered valve seat and 5 at its upper end interior threads and an offset chamber located between the ends of said passage and in communication with said passage adjacent to said interior threads and so located that the longitudinal axis of said 10 chamber is adapted to placed in a vertical plane when the body is located in an inclined position, said cup also having an external wrench receiving portion, the diameter of the passage from the valve seat to the offset 15 chamber being greater than the diameter of the interiorly threaded portion of said passage and a tapered valve adapted to engage said seat and having stem projecting through said passage and provided with threads engaging said interior threads, said valve stem 20 being insertible only from the lower end of said body and having a handle located at an angle to said body whereby the valve is normally non-detachable, the opening of the valve being, effected by lowering said valve 25 from its seat in the direction of the flow of the fluid through said passage.

Signed at Cleveland, Ohio, this 25th day of January, 1918.

OSCAR A. SMITH.
